(57) **CLAIM**

The ornamental design for a photography tripod as shown and described.

DESCRIPTION

FIG. 1 is a front, left and top perspective view of a photography tripod showing our new design;

FIG. 2 is a rear, right and bottom perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof;

FIG. 8 is a bottom plan view thereof;

FIG. 9 is an enlarged view of a portion labeled as 9 on FIG. 1;

FIG. 10 is an enlarged view of a portion labeled as 10 on FIG. 1;

FIG. 11 is an enlarged view of a portion labeled as 11 on FIG. 2; and,

FIG. 12 is an enlarged view of a portion labeled as 12 on FIG. 2.

The dash-dot-dash broken lines shown in FIGS. 1, 2, 9, 10, 11, and 12 depict enlargement boundaries that form no part of the claimed design. The broken lines showing portions of the photography tripod form no part of the claimed design.

1 Claim, 12 Drawing Sheets
